UNITED STATES PATENT OFFICE.

WILLIAM E. WILD, OF LEAD CITY, DAKOTA TERRITORY.

SOCKET-WRENCH.

SPECIFICATION forming part of Letters Patent No. 247,454, dated September 20, 1881.

Application filed May 4, 1881. (Model.)

To all whom it may concern:

Be it known that I, WILLIAM E. WILD, of Lead City, in the county of Lawrence and Territory of Dakota, have invented a new and useful Improvement in Socket-Wrenches, of which the following is a full, clear, and exact description, reference being had to the drawings hereto annexed, in which—

Figure 1 is a plan view of my improvement; 10 and Fig. 2, a side elevation of the same, partly in section.

My invention relates to nut-wrenches in which the socket is provided with an interior adjustable section for adapting the socket to 15 nuts of different sizes; and my improvement consists in a certain construction and arrangement of parts by which the adjustable section shall be secured in the strongest manner compatible with lightness, simplicity of construction, and convenience in use.

As heretofore constructed, the interior adjustable section of a socket in a nut-wrench has been secured in place and operated by means of a comparatively small screw working 25 in a thumb-nut. As the screw must necessarily be smaller than the thumb-nut, it is evident that the screw cannot be enlarged so as to secure the greatest possible strength to the adjustable section, which is of the greatest 30 importance, without requiring an increase in the size of the thumb-nut in proportion; but this in a large wrench would add unnecessarily in weight and expense, not to mention the inconvenience of enlarged parts, when 35 smaller expedients will do the work just as well.

Another objection to the thumb-nut and screw is that, owing to the central position of the screw, the shank or body of the wrench 40 must be transversely recessed in the portion where great strength is required in order to accommodate the thumb-nut. The screw or cylindrical bolt, moreover, owing to the necessary strain upon the adjustable section, is not 45 adapted to hold the said section rigidly in position, and in case the wrench should slip off while being applied to a nut this section is liable to turn out of its horizontal plane and will need to be readjusted.

To overcome the above-mentioned objections 50 I construct a wrench of the following description:

Referring to the drawings, A is the socket of the wrench, B the shank, and C the handle, all of which parts can be made in one piece. The 55 socket A can be made square, as shown in the drawings, or it can be made with eight sides or any other desired number of sides. The shank B is perforated or chambered longitudinally with a square hole, into which is fitted a 60 rectangular bar, D, having the usual angular jaw or adjustable section, E, formed upon its forward end. The inner angle of the socket A is recessed to receive the jaw or section E, so that when the bar D is fully drawn back the 65 inner surface of the said section E will be flush with the adjacent parts of the inner surface of the socket A.

Upon the upper side of the rectangular bar 70 D are formed screw-teeth F, into which fit the threads of the endless screw or worm G, which is pivoted, by a screw-pivot, I, to and between the shoulder at the forward end of the handle C, and a stud or projection, H, formed upon the shank B. The lower side of the worm G projects through a small opening in the upper part 75 of the shank B, so as to mesh with the teeth of the bar D.

With this construction it will be seen that 80 the bar D may be made as large as desired, for the purpose of strengthening the adjustable section, without the necessity of increasing the size of the worm, and as this bar is rectangular it cannot turn in its socket or chamber. Consequently the adjustable section E will be 85 held in a perfectly rigid manner; and as the worm is arranged above the shank instead of being located within it, as is usually the case, the shank is thereby made stronger than where it is transversely recessed to accommodate the 90 thumb-nut.

Having thus described my improvement, what I claim as new, and desire to secure by Letters Patent, is—

1. In a socket-wrench having an adjustable 95 section inside the socket, the combination, with the section or jaw E and the rectangular rock-bar D, of the worm G, which is pivoted above

the said shank, substantially as shown and described, whereby a large bar may be operated by the smallest expedient, as set forth.

2. In a socket-wrench having an adjustable section inside the socket, the combination of 5 the shouldered handle C, the shank B, having stud H, the pivoted worm G, and rectangular rack-bar D, substantially as shown and

described, whereby the said shank shall not be weakened by unnecessary recesses, as set forth.

WILLIAM EDWARD WILD.
